(57) **CLAIM**

The ornamental design for an electrical spring connector, as shown and described.

DESCRIPTION

FIG. 1 is a perspective view of an electrical spring connector showing the new design;

FIG. 2 is a front view thereof;

FIG. 3 is a back view thereof;

FIG. 4 is a side view thereof;

FIG. 5 is a top view thereof; and,

FIG. 6 is a bottom view thereof.
